UNITED STATES PATENT OFFICE

141,083

DESIGN FOR A NAME PLATE

Ernest B. Lane, Windsor, Ontario, Canada

Application February 5, 1944, Serial No. 112,469

Term of patent 14 years

(Cl. D1—12)

To all whom it may concern:

Be it known that I, Ernest B. Lane, a citizen of the Dominion of Canada, residing at Windsor, in the county of Essex, in the Province of Ontario, Dominion of Canada, have invented a new, original, and ornamental Design for a Name Plate, of which the following is a specification, reference being had to the accompanying drawing, forming part thereof.

My design for a name plate as shown is characterized by the bevelled edges, and disposed in the back and running horizontally is an oblong checked recess having slightly inwardly bevelled side edges to receive corresponding removable letters or numerals by slightly bending the plate,

disposed on the back of the plate, and on each side of said checked recess are a series of irregular V-shaped recesses, disposed at the four corners are orifices to receive fastening means.

Fig. 1 is a front elevational view of a name plate showing the essential features of my design in full lines, the name appearing thereon is merely for illustrative purposes.

Fig. 2 is a cross-sectional view taken along the line 2—2 of Fig. 1, and on a somewhat enlarged scale.

I claim:

The ornamental design for a name plate, as shown and described.

ERNEST B. LANE.
